SWITCH CONTROL MECHANISM

Thomas M. Ball, Detroit, Mich., assignor to
Chrysler Corporation, Highland Park, Mich., a
corporation of Delaware

Original application August 24, 1940, Serial No.
354,055. Divided and this application August
7, 1941, Serial No. 405,766

13 Claims. (Cl. 200—59)

This invention relates to switch control mechanisms and refers more particularly to switch mechanism adapted for control by engine intake pressure variation, this application being a division of my copending application Serial No. 354,055 filed August 24, 1940.

One object of my invention is to provide an electrical switch controlled in an improved and simplified manner in response to predetermined speed of an engine or equivalent motor vehicle speed in a predetermined drive ratio.

Another object is to provide an improved and simplified governor effect for switch mechanism by utilizing engine intake pressure variation.

A further object is to provide a novel governor effect, as aforesaid, which will function at predetermined amount or position of engine throttle opening under control of engine intake pressure so arranged as to function independently of the load on the engine.

Another object is to provide an improved switch control in which the electric circuit is controlled by a single switch which is adapted to be overruled by the engine intake pressure. The single switch mechanism is adapted for operation by the engine throttle actuating mechanism, or other control, and is under control of the intake pressure so that the latter will render the single switch mechanism either effective or ineffective to control the circuit means by operation of the engine throttle actuating mechanism or other control which may be employed.

Further objects and advantages of my invention will be more apparent as this specification progresses, reference being had to the accompanying drawing in which:

Fig. 1 is a side elevational somewhat diagrammatic view of a motor vehicle power plant illustrating my invention applied thereto.

Fig. 2 is an enlarged somewhat diagrammatic view of my switch control mechanism.

Fig. 3 is a view similar to Fig. 2 but illustrating a modified arrangement of operating linkage.

Fig. 4 is a view generally similar to Fig. 2 but illustrating a modified arrangement of switch control mechanism.

While my invention may be employed in conjunction with various types and arrangements of mechanisms and devices, I have illustrated the principles of my invention in connection with a motor vehicle a portion of which is shown in Fig. 1 having the internal combustion engine A for driving the vehicle through any suitable drive transmitting and speed ratio changing mechanism in casings B and C.

I have illustrated my switch control mechanism for functioning in conjunction with the throttle control mechanism of the engine. By preference the arrangement is such that the accelerator pedal in moving to a predetermined position in its throttle-opening direction exercises a controlling effect on the switch mechanism, as when the accelerator pedal is brought to its fully depressed condition corresponding to approximately fully open position of the throttle valve. The gain in power delivered by the engine during the last part of the throttle opening movement is so slight that ordinarily this range may be utilized for the switch control without sacrificing car performance where it is desired to effect the switch control under conditions of maximum throttle opening. However, as it may be desired to provide a distinct switch control range for the accelerator pedal, in addition to its normal throttle-moving range, I have made provision so that my invention is equally well adapted to either arrangement and may even, if desired, be arranged for switch control at any accelerator pedal or throttle position less than that aforesaid.

Referring particularly to Figs. 1 and 2 the accelerator pedal 10 is yielding urged in its throttle closing position of release by a spring 11. The pedal is operably connected by linkage 12 with the lever 13 fixed to shaft 14 which carries the throttle valve 15 positioned in manifold down-draft riser 16 between the carburetor 17 and manifold distributing branches 18 leading to the various cylinders of the engine. At the top air inlet end of the riser is the usual air cleaner 19. That part of the intake system which extends above valve 15 may be referred to as the atmospheric side of the throttle valve while the parts below the valve extending to the engine may be referred to as the engine side of the throttle valve. When the pedal 10 is fully depressed to position 10' then the throttle is fully open as at 15'. In Fig. 2 the arrangement is such that the last few degrees of throttle opening is utilized to operate the switch means, this movement corresponding to depression of the accelerator pedal from position 10 to position 10'.

The vacuum control comprises a piston 20 of non-conducting material and is formed with a lower lug 21 which, prior to vacuum operation of piston 20, urges a swinging spring conductor 22 portion of a switch E downwardly against the upper face of the fixed non-conducting material 23. The conductor 22 is carried by a plunger 24 and is yielding moved to the Fig. 2 position by spring 25. Fixed to the throttle shaft 14 is a

lever 28 having an actuating end portion 27 arranged to engage the rear end of plunger 24 when the accelerator pedal on throttle opening movement reaches the position 10'. When the accelerator pedal is further depressed to position 10", plunger 24 and conductor 22 slide to the left, by the action of lever end 27, until at the end of the pedal stroke the conductor end 28 contacts with conductor terminal 29, comprising the other portion of the switch E.

Associated with the switch E is any suitable electrical circuit system desired to be controlled by the switch under predetermined desired conditions of throttle opening and car or engine speed. I have illustrated a portion of this electrical circuit at D comprising ground 30 thence through conductor 22 and end 28 to terminal 29 and conductor lead 31 to any desired electrical control to complete the circuit. The switch E is under control of the intake system of the engine according to predetermined desired conditions of engine and car speed.

The piston 20 is slidable upwardly from its Fig. 2 position in cylinder 32 against the action of spring 33 as vacuum increases in the intake system at the atmospheric side of the throttle valve.

In order to magnify the effect of the vacuum in riser 16 and minimize the size of piston 20, while at the same time utilizing structure already used conventionally, and for other practical considerations, I utilize the conventional carburetor venturi 34 in down draft riser 16, the cylinder 32 being open by a passage 35 to the throat of the venturi.

Cylinder 32 thus communicates with the engine intake system at a point between throttle valve 15 and the atmosphere rather than between the throttle valve 15 and the engine A so that, for a given throttle opening, the same weight of air will always flow through the carburetor venturi at a given speed of the engine or car in any given drive ratio, regardless of load and other factors. Cylinder 32 is thus open to the suction in the intake riser at a point anterior to the throttle valve 15 rather than at a point posterior to the throttle valve. For simplicity of disclosure I have not illustrated the gasoline supply jet at the carburetor Venturi throat as the same is well known. Such arrangement provides a governor control on the system D at switch E of great accuracy and simplicity of operation.

In the illustrated arrangement, the driver endeavors to control circuit D by closing switch E always by manipulating the throttle valve 15 to the same position, approximately wide open throttle in this instance, because at such time the switch E will be closed if piston 20 is in its Fig. 2 lowered position. Thus whether or not the circuit D will be closed between lead 31 and ground 30, when the accelerator pedal 10 is fully depressed, will depend entirely on the engine or car speed at such time. If the speed is above the desired predetermined value, determined largely by the weight of piston 20 along with the force of springs 33 and 22 and diameter of cylinder 32, then the vacuum at the venturi raises piston 20 and conductor 22 flexes or springs upwardly out of contact with material 23 and cannot complete the circuit at terminal 29 although plunger 24 is free to reciprocate under action of the accelerator pedal and spring 25. If, while piston 20 is raised and pedal 10 is fully depressed, the engine speed falls to the point where piston 20 is lowered by spring 33, then the conductor part 28 contacts

with terminal 29 and thereupon establishes the circuit D. The conductor 22 therefore constitutes a switch at E in that it controls the circuit D.

My arrangement is such that the switch points 5 at 28 and 29 are free from thrust load imposed from the accelerator pedal at lever end 27 because the end of spring member 22 does not thrust against any electrical contact in the direction of movement of member 22 by lever end 10 27.

In the Fig. 3 modification, the switch E is not closed when the throttle valve on opening reaches wide open position but in response to movement of the accelerator pedal 10 beyond its wide open 15 throttle position 10' through a secondary range of movement to position 10" at which time the lever end portion 27 of a lever 26 has been moved to the left of its Fig. 3 position sufficiently to cause plunger 24 to close switch E. The pedal 20 10 is now connected through linkage 12 to the bell-crank lever arm 37 loose on the valve shaft 14, lever 38 being the other arm of the bell-crank. Fixed to shaft 14 is a lever 38 having a projection 39 urged into continuous contact with lever 37 25 by a spring 40 acting between levers 37 and 38. A stop 41 engages lever 38 at fully open throttle.

When pedal 10 is depressed to position 10' the throttle valve 15 will be fully open, as at 15' in Fig. 2, the spring 40 causing lever 38 to follow 30 the movement of lever 37 and pedal 10. At this time the lever end 27 is in its Fig. 3 position ready to operate plunger 24 to the left. As pedal 10 is further depressed to the overtravel position 10", stop 41 holds lever 38 at wide open throttle 35 position while spring 40 yields to allow lever 38 to close switch E unless, just as in Fig. 2, piston 20 is raised to allow spring conductor 22 to flex out of the path to engage terminal 29. The Fig. 3 switch control system operates exactly as described for Fig. 2 except, of course, for the overtravel function of the accelerator pedal as noted above.

My invention is also adapted to control electrical systems wherein the electrical circuit is 45 normally established and adapted to be opened by the throttle opening means under control of the vacuum intake system. In order to illustrate this general arrangement, I have shown in Fig. 4 an arrangement which corresponds generally 50 to the foregoing embodiments but which operates with normally closed switch means instead of normally open switch means. Thus in Fig. 4, the swinging spring conductor 22' now has its left 55 end, forming a part of switch E', in engagement with an angle shaped conductor surface or switch terminal 29' so arranged that when plunger 20 is down then the circuit at D is established and will remain established even though vacuum should raise the piston and the spring conductor 60 22' thereby flex upwardly as indicated in the drawing. Lever end 27, when operated to move conductor 22' to the left, will open the circuit if the piston 20 is down. However, if the piston is raised to allow the conductor 22' to spring 65 upwardly, the circuit will remain closed even though the lever end 27 is operated to the left.

In Figs. 2 to 4 it will be noted that whenever the driver seeks to change the normal condition of switch E or E', by closing the same in Figs. 2 70 and 3 and by opening the same in Fig. 4, the throttle valve 15 in each instance is at a predetermined position so that the vacuum device will, in effect, then operate as a fixed function of engine speed and hence car speed in any predetermined drive ratio. If desired, the normal condi-

tion of the switch E or E' may be changed at less than approximate wide open throttle. Furthermore, by substituting different piston springs for the vacuum operated pistons the illustrated devices may be caused to respond to any desired engine or car speed.

In my specification and claims I use the term "venturi" in a broad sense. This device, as well known, increases the velocity and reduces the pressure of the fluid at the Venturi throat. The venturi may be of any suitable design to obtain the desired pressure magnifying effect. Ordinarily a commercial carburetor venturi is formed with frusto-conical portions at each side of the throat as illustrated. The various conductor parts throughout the several views will, of course, be suitably electrically insulated against undesired grounding or interfering with the desired electrical control systems.

In Figs. 2, 3 and 4 the pressure variation at the venturi operates to overrule the effect of the throttle adjusting means in controlling opening and closing of the electrical circuit means at the switch E or E'. In other words the venturi control renders the switch E or E' either effective or ineffective to control opening and closing of the circuit means.

I claim:

1. In a switch control mechanism, electric circuit means comprising a switch having a spring conductor adapted to be flexed between two positions in only one of which positions said conductor is adapted for movement for switch-opening and switch-closing functions, means for moving said conductor as aforesaid, an engine having an intake system provided with a throttle valve for controlling air flow from the atmosphere to the engine, and means responsive to pressure variation in said intake system at a point anterior to said throttle valve for controlling flexing of said conductor such that flexing of said conductor from its said one position to the other will be automatically effected, during operation of said engine under its own power, as a function of engine speed higher than the engine idling speed.

2. In a switch control mechanism; a switch comprising a relatively stationarily mounted conductor switch member, and a conductor spring switch member adapted to be flexed between two positions in only one of which positions said conductor is adapted for movement relative to said stationary switch member into locations of engaging and disengaging relationship with respect to said stationary switch member to respectively provide closing and opening of said switch; operating means for displacing said spring conductor member between said locations; a piston adapted for movement from a first position of maintaining said spring switch member flexed in its said one position to a second piston position accommodating flexing of said spring switch member out of engageable relationship with respect to said stationary switch member when said spring switch member is displaced by said operating means; an engine having an intake system provided with a throttle valve for controlling air flow from the atmosphere to the engine; means utilizing pressure variation in said intake system at the atmospheric side of said throttle valve for moving said piston from its said first position to its said second position; and means for biasing said piston to its said first position and operating to hold said piston in its said first position whenever the engine is idling.

3. In a switch control mechanism; a switch comprising a relatively stationarily mounted conductor switch member, and a conductor spring switch member adapted to be flexed between two positions in only one of which positions said conductor is adapted for movement relative to said stationary switch member into locations of engaging and disengaging relationship with respect to said stationary switch member to respectively provide closing and opening of said switch; operating means for displacing said spring conductor member between said locations; a piston adapted for movement from a first position of maintaining said spring switch member flexed in its said one position to a second piston position accommodating flexing of said spring switch member out of engageable relationship with respect to said stationary switch member when said spring switch member is displaced by said operating means; an engine having an intake system provided with a throttle valve for controlling air flow from the atmosphere to the engine; means utilizing pressure variation in said intake system at the atmospheric side of said throttle valve for moving said piston from its said first position to its said second position; and means for biasing said piston to its said first position and operating to hold said piston in its said first position whenever the engine is idling.
4. In a switch control mechanism, electric circuit means comprising a switch having a spring conductor adapted to be flexed between two positions in only one of which positions said conductor is adapted for movement for switch-opening and switch-closing functions, means for moving said conductor as aforesaid, an engine having an induction system provided with a throttle valve and a carburetor venturi disposed anterior to said throttle valve, and means responsive to pressure variation at said venturi for so controlling flexing of said conductor that flexing of said conductor from its said one position to the other is automatically effected, during normal operation of said engine, in response to predetermined throttle opening and engine speed greater than idling speed.
5. In a switch control mechanism, electric circuit means comprising a switch having a spring conductor adapted to be flexed between two positions in only one of which positions said conductor is adapted for movement for switch-opening and switch-closing functions, means for moving said conductor as aforesaid, and engine having an intake system provided with a throttle valve for controlling air flow from the atmosphere to the engine, and means utilizing pressure variation in said intake system at the atmospheric side of said throttle valve for controlling flexing of said conductor from time to time during normal operation of said engine.
6. In a switch control mechanism, electric circuit means comprising a switch having a spring conductor adapted to be flexed between two positions in only one of which positions said conductor is adapted for movement for switch-opening and switch-closing functions, an engine having an intake system provided with a throttle valve for controlling air flow from the atmosphere to the engine, means for adjusting said throttle valve, means for moving said conductor as aforesaid by said throttle valve adjusting means, and means utilizing pressure variation in said intake system at the atmospheric side of said throttle valve for so controlling flexing

of said conductor that flexing of said conductor from its said one position to the other is automatically effected, during normal operation of said engine, in response to predetermined throttle opening and engine speed greater than idling speed.

7. In a switch control mechanism; a switch comprising a relatively stationarily mounted conductor switch member, and a conductor spring switch member adapted to be flexed between two positions in only one of which positions said conductor is adapted for movement relative to said stationary switch member into locations of engaging and disengaging relationship with respect to said stationary switch member to respectively provide closing and opening of said switch; operating means for displacing said spring conductor member between said locations; a piston adapted for movement from a first position of maintaining said spring switch member flexed in its said one position to a second piston position accommodating flexing of said spring switch member out of engageable relationship with respect to said stationary switch member when said spring switch member is displaced by said operating means; an engine having an induction system provided with a throttle valve and a carburetor venturi disposed anterior to said throttle valve; means utilizing pressure variation at said venturi for moving said piston from its said first position to its said second position; and means for biasing said piston to its said first position and operating to hold said piston in its said first position whenever the engine is idling.

8. In a switch control mechanism; a switch comprising a relatively stationarily mounted conductor switch member, and a conductor spring switch member adapted to be flexed between two positions in only one of which positions said conductor is adapted for movement relative to said stationary switch member into locations of engaging and disengaging relationship with respect to said stationary switch member to respectively provide closing and opening of said switch; operating means for displacing said spring conductor member between said locations; a piston adapted for movement from a first position of maintaining said spring switch member flexed in its said one position to a second piston position accommodating flexing of said spring switch member into its other position of constant engagement with said stationary switch member when said spring switch member is displaced by said operating means; an engine having an induction system provided with a throttle valve and a carburetor venturi disposed anterior to said throttle valve; means utilizing pressure variation at said venturi for moving said piston from its said first position to its said second position; and means for biasing said piston to its said first position and operating to hold said piston in its said first position whenever the engine is idling.

9. In a switch control mechanism, electric circuit means comprising a switch having a spring conductor adapted to be flexed between two positions in only one of which positions said conductor is adapted for movement for switch-opening and switch-closing functions, an engine having an intake system provided with a throttle valve for controlling air flow from the atmosphere to the engine, means for adjusting said throttle valve comprising an accelerator pedal movable to a position of approximately effective

wide open throttle position and therebeyond to a second position overtravelling said throttle valve in said effective wide open position, means for moving said conductor as aforesaid by said 5 adjusting means in response to movement of said pedal for said overtravel, and means utilizing pressure variation in said intake system at the atmospheric side of said throttle valve for so 10 controlling flexing of said conductor that flexing of said conductor from its said one position to the other, will be automatically effected, during operation of said engine under its own power, in response to adjustment of said throttle valve to its said effective wide open position attended 15 by operation of said engine at a predetermined speed higher than engine idling speed.

10. In a switch control mechanism, electric circuit means comprising a switch having a swinging conductor adapted to be biased between 20 two positions in only one of which positions said swinging conductor is adapted for reciprocating movement for switch-opening and switch-closing functions, support means for supporting said swinging conductor for swinging movement 25 thereof to each of said positions, means for reciprocating said swinging conductor as aforesaid, a relatively fixed conductor so constructed and arranged in relationship with said swinging conductor that when said swinging conductor is in its said one position then operation 30 of said reciprocating means effects make and break contact of said swinging conductor with respect to said fixed conductor and when said swinging conductor is in the other of its said 35 positions then said swinging conductor will not engage said fixed conductor when said swinging conductor is reciprocated by said reciprocating means, an engine having an intake system provided with a throttle valve for controlling air 40 flow from the atmosphere to the engine, differential pressure operating means utilizing pressure in said intake system at the atmospheric side of said throttle valve for effecting swinging of said swinging conductor to its said other position, and means biasing said swinging conductor to its said one position and operating to 45 prevent said differential pressure operating means from effecting said swinging of said swinging conductor to its said other position 50 unless, when the engine is operating at predetermined speed greater than its idling speed, the throttle valve is disposed in predetermined throttle open position.

11. In a switch control mechanism, a relatively stationarily mounted electrical conductor, a second electrical conductor adapted for movement in a predetermined path for engagement and disengagement with respect to said stationary conductor, means mounting said second 55 conductor for displacement thereof out of said path, an engine having an intake system provided with a carburetor of fuel mixture venturi, and means responsive to pressure variation in said intake system at the throat of said venturi 60 for so controlling said displacement of said second conductor that displacement of said second conductor out of said path will be automatically effected during operation of said engine under its own power, as a function of engine speed 65 higher than engine idling speed.

12. In a switch control mechanism, a relatively stationarily mounted electrical conductor, a second electrical conductor adapted for movement in a predetermined path for engagement 70 and disengagement with respect to said station-

ary conductor, means mounting said second conductor for displacement thereof out of said path, an engine having an intake system provided with a throttle valve for controlling air flow from the atmosphere to the engine, and means utilizing pressure variation in said intake system at the atmospheric side of said throttle valve for so controlling displacement of said second conductor that displacement of said second conductor out of said path will be automatically effected during normal operation of said engine, in response to predetermined opening of said throttle valve attended by a predetermined engine speed greater than idling speed.

13. In a switch control mechanism, a stationary electrical conductor, a movable electrical conductor adapted for displacement between two positions in each of which said movable conductor is adapted for movement in relatively different predetermined paths each generally

transverse to the path of said displacement, said movable conductor being so disposed in relation to said stationary conductor that said movable conductor will engage and disengage said stationary conductor only when said movable conductor is moved in one of said predetermined paths, an actuating element for effecting movement of said movable conductor in said predetermined paths, an engine having an intake system provided with a throttle valve for controlling air flow from the atmosphere to the engine, differential pressure operating means utilizing pressure in said intake system at the atmospheric side of said throttle valve for effecting displacement of said movable conductor to one of its said positions, and means biasing said movable conductor to the other of its said positions of displacement.

THOMAS M. BALL.
